UNITED STATES PATENT OFFICE

JOHN R. GOULD, OF ALDWYCH, LONDON, ENGLAND, ASSIGNOR TO WESTERN ELECTRIC COMPANY, INCORPORATED, OF NEW YORK, N. Y., A CORPORATION OF NEW YORK

TELEPHONE SYSTEM

Application filed March 14, 1929, Serial No. 346,825, and in Great Britain March 28, 1928.

This invention relates to telephone systems and more particularly to systems in which connections are established by the use of automatic switches.

5 The object of this invention is to simplify and otherwise improve the equipment employed for setting up connections to subscribers' lines in systems having numbers with a uniform or a variable number of digits.

10 Heretofore two-motion distributor switches have been provided in four-digit areas to give a toll, long distance or test operator access to final selectors which can make connection with a wanted subscriber's line irrespective of its idle or busy condition. The toll or long 15 distance operator is thus able to inform a subscriber who is engaged in conversation on a local call that there is a toll or long distance call waiting for completion, and the test operator is able at all times to test any line to which the distributor and final selectors give access. The distributor switch is selectively operated by the two series of pulses which are originated by the dialing of the first two 20 digits of the number of the required line to make connection with a final selector which has access to the required line. The final selector, if found idle, is thereafter operated in accordance with the last two digits of the 25 number to seize the required line irrespective of the busy or idle condition of this line.

According to one feature of this invention a two-motion distributor switch is arranged 30 to give access to lines all of which have five-digit numbers without the use of an additional selector in series with the distributor switch and final selector.

According to a second feature of this invention a distributor switch is provided for giving access to lines having four-digit numbers and to lines having five-digit numbers, said switch being arranged to discriminate 35 between four-digit and five-digit numbers.

40 According to another feature a secondary distributor switch is used in combination with a main distributor switch to give access to lines having four-digit numbers and to lines having five-digit numbers, means being provided to discriminate between the four-digit

and the five-digit numbers. Lines having four-digit numbers are reached through the secondary switch and lines having five-digit numbers are reached through the main switch.

45 A further feature of the invention relates to the provision of an auxiliary switch in combination with a main distributor switch for giving access to a total number of lines having five-digit numbers which exceeds the 50 capacity of the main switch alone. Switching means are provided for transferring from the main to the auxiliary switch when the line with which connection is required is accessible through the auxiliary switch.

55 Referring to the drawings, a trunk-offering operator's cord is shown diagrammatically at A in Fig. 1 and a distributor circuit is shown at D in Figs. 1 and 2. The distributor circuit includes a main distributor switch M, a secondary distributor switch S, and a tertiary distributor switch T all of which are shown diagrammatically in Fig. 2. A final selector F and a called subscriber's station are also shown in Fig. 2. Fig. 3 60 shows apparatus and wiring which is added at the sections AA—A'A' in Fig. 2 when required to meet certain conditions as herein-after described.

65 Each of the distributor switches M, S, and T includes a set of six brushes and an associated bank of terminals, vertical off-normal springs VON, a vertical stepping magnet, a rotary stepping magnet, and a release magnet. The corresponding brushes of switches M, S, and T are connected in multiple. The sets of terminals in the bank of switch M connect to final selector circuits which in some of the cases hereinafter described give access 70 to groups of lines having four-digit numbers and in other cases give access to groups of lines having five-digit numbers. The sets of terminals in the bank of switch S connect either to final selectors which give access to groups of lines having four-digit numbers or connect through a high resistance to battery 75 as a means for distinguishing between a four-digit and a five-digit number. The sets of terminals in the bank of switch T connect to 80

final selectors which give access to groups of lines having five-digit numbers.

The apparatus and wiring shown in Figs. 1, 2 and 3 provide distributor facilities for giving the trunk-offering operator at A access to offices in which all of the lines have five-digit numbers and to offices in which some of the lines have four-digit numbers and some have five-digit numbers providing that the four-digit numbers and the five-digit numbers always differ in the first two digits and that the first two digits of all numbers run consecutively. The cases which arise may be classified as follows: (a) Offices having both four-digit and five-digit numbers. The four-digit numbers have different first digits and their total does not exceed 10,000 i. e. 2000-4899. The five-digit numbers have two different first digits, of which one may or may not be the same as the highest or the lowest first digit of the four-digit numbers, and their total exceeds 10,000 but does not exceed 20,000 i. e. 49,000-59,999. (b) Offices having both four-digit and five-digit numbers. The four-digit numbers have different first digits and their total does not exceed 10,000 i. e. 2000-4899. The five-digit numbers have two different first digits, of which one may or may not be the same as the highest or the lowest first digit of the four-digit numbers, and their total does not exceed 10,000 i. e. 49,000-58,999. (c) Offices having both four-digit and five-digit numbers. The four-digit numbers have different first digits and their total does not exceed 10,000 i. e. 2000-4899. All five-digit numbers have the same first digit and this digit is either the highest or the lowest of the first digits of the four-digit numbers i. e. 49,000-42,999. The total of both four-digit and five-digit numbers does not exceed 10,000. (d) Offices having both four-digit and five-digit numbers, the first digit of all numbers being the same (as in a main office and its satellites) i. e. 6100-6699 and 67,000-69,999. The total of all numbers does not exceed 10,000. (e) Offices in which all numbers are five-digit numbers and their total does not exceed 10,000, i. e. 52,000-59,999. (f) Offices in which all numbers are five-digit numbers and their total does not exceed 10,000 but does not exceed 20,000, i. e. 50,000-62,999.

The operation of the circuits shown in Figs. 1 and 2 for giving the trunk-offering operator at A access to an office of the above mentioned class (a) will now be described in detail. In such an office the lines having four-digit numbers, i. e. from 2000 to 4899 inclusive, are accessible through sets of terminals in the bank of switch S; lines having five-digit numbers whose first digit is the same as the first digit of some of the four-digit numbers, i. e. from 49,000 to 49,999 inclusive, are accessible through sets of terminals in the bank of switch M, and the lines

having five-digit numbers whose first digit is different from the first digits of the four-digit numbers, i. e. from 50,000 to 59,999 inclusive, are accessible through sets of terminals in the bank of switch T. When the first digit of the called number is dialed the brushes of switches M and S are stepped up to the corresponding level. The shaft and brushes of switch M are then returned to normal and the pulses originated by the dialing of the second digit step the brushes of switch M in a vertical direction and at the same time step the brushes of switch S in a rotary direction into contact with the corresponding set of terminals in the previously selected level. If the called number is a four-digit number the terminals with which the brushes of switch S are in contact connect to a final selector which has access to the line having the called number. If the number is a five digit number whose first digit is the same as the first digit of some of the four-digit numbers, one of the terminals with which the brushes of the switch S are in contact is permanently connected through a high resistance to battery, this arrangement being effective to prevent the further operation of switch S. When the third digit of the called number is dialed the brushes of switch M are stepped in a rotary direction into contact with a set of terminals which connect to a final selector having access to the line of the called number. If the number is a five-digit number whose first digit is different from the first digits of the four-digit numbers level-springs NP are actuated when the brushes of switch M are stepped up to that level and the further operation of switches M and S is thereby prevented. Thereafter switch T, only, is actuated in response to the dialing of the second and third digits of the called number to advance its brushes into contact with a set of terminals which connect to a final selector having access to the line of the called number. (For an office within class (a) the NPA springs and Fig. 3 are omitted.)

When the operator at A inserts plug 7 in jack 8 connection is obtained over trunk 9 with the distributor circuit D which is located in the office in which the called subscriber's line terminates. Relay 5 in the cord circuit operates to ground on the sleeve of jack 8. Relay 4 in the cord circuit and relay 12 in the distributor circuit are operated in an obvious circuit over the tip side of the trunk. Relay 14 in the distributor circuit operates over the ring side of the trunk in a circuit which may be traced from grounded battery through one winding of the repeating coil and through the normally closed contacts of dial key 1 in the cord circuit, over the ring side of the trunk 9, through the winding of relay 14, lead 19, normally closed contacts of the vertical off-

normal springs 220, 120 and 20 of switches T, S and M, respectively, back contact and right hand armature of relay 35, and through the normally closed contacts of the continuity springs of relay 15, to ground. The operation of relay 14 closes an obvious circuit for operating relay 15. The operation of relay 15 connects ground through the normally open contacts of its continuity springs directly to the winding of relay 14 so that relay 14 holds independent of the VON springs of switches M, S and T.

After operating dial key 1, the trunk-offering operator dials the number of the subscriber's station with which connection is desired. The operation of the dial 2 opens and closes the circuit over the ring side of trunk 9 thereby causing the alternate release and re-operation of relay 14. Relay 15 is a slow-to-release relay and therefore it does not release during dialing. The first release of relay 14 causes the operation of relay 16, vertical stepping magnet 27 of switch M, and vertical stepping magnet 127 of switch S. The circuit for relay 16 may be traced from battery through its winding, lead 17, front contact and inner right-hand armature of relay 15, back contact and inner right-hand armature of relay 14, to ground. The circuit for vertical magnet 27 may be traced from battery through its winding, back contact and inner left-hand armature of relay 230, back contact and next-to-the-outer right-hand armature of relay 33, back contact and inner right-hand armature of relay 30, middle left-hand armature and back contact of relay 32, middle lower armature and back contact of relay 34, to ground on lead 17. The circuit for vertical magnet 127 may be traced from battery through its winding, back contact and outer right-hand armature of relay 36, outer right-hand armature and back contact of relay 14, back contact and next-to-the-inner right-hand armature of relay 37, and through the front contact and next-to-the-inner right-hand armature of relay 15, to ground. Relay 16 is also a slow-to-release relay and therefore it does not release until all of the pulses originated by the dialing of any one digit have all been received. The vertical magnets 27 and 127 operate and release each time relay 14 releases and re-operates, thus stepping the brushes of switch M and the brushes of switch S up to the level which corresponds to the first digit of the called number. The vertical off-normal springs of switches M and S are operated as soon as their shafts are stepped out of their normal positions. Relay 36 which is a two-stage relay is partially operated in a circuit from battery through its left-hand winding, back contact and middle right-hand armature, contact of the VON springs 18, to ground on lead 19. When thus partially operated a circuit is closed from battery through

both of its windings in series and through its front contact and left-hand armature to ground at relay 15, but the right-hand winding of relay 36 is short circuited through the contacts of VON springs 18 until the shaft and brushes of switch M are returned to normal as hereinafter described.

When relay 16 releases after all of the pulses originated by the dialing of the first digit have been received, relay 30 operates in a circuit which may be traced from battery through its winding, back contact and right-hand armature of relay 31, normally closed contacts of the continuity springs of relay 16, contacts of VON springs 18 to ground on lead 19. The operation of relay 30 at this time performs no useful function. The release of relay 16 also causes the operation of release magnet 29 of switch M in a circuit which may be traced from battery, through its winding, front contact and outer right-hand armature of relay 15, back contact and next-to-the-inner right-hand armature of relay 36, normally closed contacts of the continuity springs of relay 16, and through the contacts of VON springs 18, to ground on lead 19. The shaft, brushes, and VON springs of switch M are, therefore, returned to normal, thus causing the release of relay 30 and the complete operation of relay 36 through both windings in series to ground at relay 15.

When the second digit of the called number is dialed, relays 14, 15 and 16 function in the same manner as when the first digit was dialed. The vertical magnet 27 of switch M is reoperated, stepping the brushes of switch M up to the level corresponding to the second digit, and the rotary magnet 128 of switch S is operated to step the brushes of switch S into contact with the corresponding set of terminals in the previously selected level. The circuit for operating the rotary magnet 128 of switch S may be traced from battery through its winding, front contact and outer right-hand armature of relay 36, outer right-hand armature and back contact of relay 14, back contact and next-to-the-inner right-hand armature of relay 37, to ground at relay 15. Relay 16 releases when all of the pulses originated by the dialing of the second digit have been received, thereby operating relay 30 as hereinbefore described.

If the second digit is one which characterizes the called number as being a four-digit number, brushes 121, 122, 123, 124, 125 and 126 are in contact with a set of terminals which connect to a final selector. If this selector is busy brush 124 encounters a busy potential on the terminal with which it is in contact, this terminal being connected through a low resistance to battery as a busy potential. In this event relay 37 is operated in a circuit from this busy potential, through brush 124, back contact and inner right-hand

armature of relay 16, left-hand armature, back contact, and left-hand winding of relay 37, to ground. Relay 37 locks through its right-hand winding, front contact and inner right-hand armature to ground at relay 15, 5 opens the circuit from brush 124 to its left-hand winding, and closes a circuit from brush 124 through its left-hand armature and front contact, normally closed right-hand contacts 10 and winding of relay 32, next-to-the-outer left-hand armature and back contact of relay 33, to ground at relay 15. Relay 32 operates in this circuit and locks to battery through its own continuity contacts. The operation of 15 relay 32 connects the ring side of trunk 9, through condenser 11, front contact and next-to-the-outer left-hand armature of relay 32, next-to-the-inner left-hand armature and back contact of relay 33, and through condenser 40 20 to the secondary winding of busy tone transformer BT. Busy tone is thereby transmitted to the trunk-offering operator's cord circuit at A.

If the final selector (which is connected to 25 the set of terminals with which the brushes of switch S are in contact) is idle the brush 124 does not encounter a busy potential and relays 37 and 32 are not operated. In this event relay 31 is operated in a circuit from battery 30 through its winding, back contact and outer right-hand armature of relay 37, front contact and inner right-hand armature of relay 36, back contact and outer right-hand armature of relay 16, front contact and outer right-hand armature of relay 30, contacts of the 35 VON springs 18, to ground on lead 19. Relay 31 locks through its front contacts and right-hand armature and through the normally closed contacts of the continuity springs of 40 relay 16, to the same ground on lead 19. The operation of relay 31 causes the release of relay 30. With relay 30 released a circuit is closed from battery through the winding of relay 33, back contact and next-to-the-inner left-hand armature of relay 32, front contact and outer left-hand armature of relay 31, back contact and outer right-hand armature of relay 30, and through the contacts of 45 VON springs 18, to ground on lead 19. Relay 33 operates in this circuit and locks through its front contact and inner left-hand armature, to the same ground. The operation of relay 33 causes the operation of relay 35 in an obvious circuit, and connects the 50 pulsing circuit (through brush 126) to the vertical magnet (not shown) of the final selector, connects busy (low resistance battery) potential through its outer left-hand armature and front contact to brush 124, connects the winding of test relay 32 through 55 brush 123 to the sleeve brush of the final selector, and causes the operation of relay 37 in a circuit from battery through the outer left-hand armature and front contact of relay 33, back contact and inner right-hand 60

armature of relay 16, and through the left-hand armature, back contact, and left-hand winding of relay 37, to ground. Relay 37 locks through its right-hand winding to ground at relay 15.

When the third digit of the four-digit number is dialed relays 14, 15 and 16 function in the same manner as when the first digit was dialed and the vertical stepping magnet (not shown) of the final selector is operated to step the brushes of the final selector up to the corresponding level. The circuit for this vertical magnet may be traced from brush 126, through the front contact and next-to-the-outer right-hand armature of relay 33, back contact and inner right-hand armature of relay 30, middle left-hand armature and back contact of relay 32, middle lower armature and back contact of relay 34, to ground on lead 17. The operation of relay 16, on receipt of the first pulse, causes the release of relay 31 and the release of relay 16, when all of the pulses originated by the dialing of the third digit have been received, causes the reoperation of relay 30. Relay 31 cannot now re-operate through the contacts of relay 37 since relay 37 is operated.

When the fourth digit of the called member is dialed relays 14, 15 and 16 function in the same manner as when the first digit was dialed and the rotary stepping magnet (not shown) of the final selector is operated to step the brushes of the selector into contact with the set of terminals to which the line of the called number is connected. The circuit for operating the rotary stepping magnet is traced from brush 125, through the front contact and next-to-the-inner right-hand armature of relay 33, front contact and inner right-hand armature of relay 30, to ground as traced for the operation of the vertical magnet. The operation of relay 16 closes a holding circuit for relay 30 and an operating circuit for relay 31. The circuit for holding relay 30 may be traced from battery through its winding, front contact and left-hand armature, and through the middle right-hand armature and front contact of relay 16, contacts of VON springs 18, to ground on lead 19. The circuit for operating relay 31 may be traced from battery through its winding, front contact and outer right-hand armature of relay 16, front contact and outer right-hand armature of relay 30, contacts of VON springs 18, to ground on lead 19. When relay 16 releases after all of the pulses originated by the dialing of the fourth digit have been received, relay 30 is released and relay 31 is locked through its front contact and right-hand armature, and through the normally closed contacts of the continuity springs of relay 16, to ground on lead 19. Relay 30 is slow to release so that the release of relay 16 closes a circuit from battery through the winding of relay 34, front contact and inner right-hand armature of relay 30, to ground on lead 19. The circuit for operating relay 32 may be traced from battery through its winding, front contact and outer right-hand armature of relay 16, front contact and outer right-hand armature of relay 30, contacts of VON springs 18, to ground on lead 19. When relay 16 releases after all of the pulses originated by the dialing of the fourth digit have been received, relay 30 is released and relay 31 is locked through its front contact and right-hand armature, and through the normally closed contacts of the continuity springs of relay 16, to ground on lead 19. Relay 30 is slow to release so that the release of relay 16 closes a circuit from battery through the winding of relay 34, front contact and inner right-hand armature of relay 30, to ground on lead 19.

tact and inner right-hand armature of relay 33, front contact and inner left-hand armature of relay 31, back contact and outer right-hand armature of relay 16, front contact and outer right-hand armature of relay 30, contacts of VON springs 18, to ground on lead 19. Relay 34 operates in this circuit connecting the tip and ring sides of trunk 9, through condensers 10 and 11, front contacts and upper armatures of relay 34, brushes 121 and 122, and through the brushes of final selector F, to the line of the called station B. Relay 34 locks through its front contact and inner lower armature and through the front contact and inner left-hand armature of relay 33, contacts of VON springs 18, to ground on lead 19. The release of relay 16 also closes the busy test circuit from the sleeve brush of the final selector, through brush 123, front contact and next-to-the-outer left-hand armature of relay 33, winding and normally closed right-hand contacts of relay 32, front contacts and left-hand armature of relay 37, inner right-hand armature and back contact of relay 16, and through the front contact and outer left-hand armature of relay 33, to battery. If the called line is busy (which it is, since this is a trunk-offering call) the sleeve brush of the final selector encounters a busy (ground) potential and relay 32 operates in the busy test circuit. Relay 32 locks through its front contact and right-hand armature, holds the circuit for relay 12 closed after relay 34 has operated, and closes a loop through resistance 41 across the tip and ring leads from the final selector.

The trunk-offering operator now offers the waiting trunk call to the called subscriber. When the subscribers release the connection which has been holding the called line busy, the busy potential is removed from the sleeve terminal of the line and test relay 32 is released. The release of relay 32 disconnects relay 12 from the tip side of trunk 9, thereby causing the release of relay 4 and the consequent lighting of supervisory lamp 6 in the operator's cord circuit. When the operator removes the plug 7 from jack 8, relay 5 releases and lamp 6 is extinguished. The trunk call is then completed over the regular train of switches.

The removal of plug 7 from jack 8 releases relay 14 in the distributor circuit and also releases relay 12 if not already released. The release of relay 14 opens the circuit for relay 15. The release of relay 15 disconnects ground from relay 14 thereby preventing the reoperation of relay 14 until the release of the distributor switches has been completed. The release of relay 15 also disconnects ground from lead 19 thereby releasing relays 34, 33, 32 and 31 if operated. If relay 33 was operated, before release of the distributor circuit, relay 35 was also operated and relay 35 now holds in a circuit from ground at the

normally closed contacts of relay 15, through the armature, front contact and right-hand winding of relay 35, brush 124, winding of the release magnet (not shown) of the final selector, to battery. The release magnet of the selector operates in this circuit causing the return of the final selector to normal. When the shaft and brushes of the selector reach their normal position the circuit through the release magnet and winding of relay 35 is opened. The release of relay 35 causes the operation of release magnet 29 of switch M in a circuit from battery through its winding, contacts of VON springs 20, back contact and armature of relay 35, to ground at relay 15. The operation of magnet 29 returns the shaft and brushes of switch M to normal, thereby opening the circuit of release magnet 29 at the contacts of VON springs 20. VON springs 13 and 18 are also returned to their normal positions. With switch M normal, the release magnet 129 of switch S operates in a circuit through the front contact of VON springs 120 and through the normally closed contacts of VON springs 20, to ground as described for operating magnet 29. The operation of magnet 129 returns the shaft and brushes of switch S to normal, thereby opening the circuit of release magnet 129. With the VON springs 120 in their normal position ground is connected to the winding of relay 14 in readiness for another call.

If the second digit of the called number were such as to characterize the number as being a five-digit number instead of a four-digit number as was assumed in the foregoing description, the set of terminals, with which the brushes of switch S have been stepped into contact, do not connect to a final selector, and the brush 124 encounters a high resistance battery potential which is effective to operate relay 37, as hereinbefore described and as soon as relay 16 releases after all of the pulses originated by the dialing of the second digit have been received. Relay 37 locks through its right-hand winding to ground at relay 15 and connects the winding of test relay 32 to brush 124 but relay 32 is marginal and does not operate since the circuit through brush 124 is traced to battery through a high resistance. The operation of relay 37 also prevents the further operation of switch S when the third, fourth and fifth digits are dialed. When the third digit is dialed relays 14, 15 and 16 function in the same manner as when the first digit was dialed and the rotary stepping magnet 28 of switch M is operated to advance the brushes of switch M into contact with the corresponding set of terminals which connect to a final selector having access to the line of the called number. The operation of relay 16, on receipt of the first pulse, closes the holding circuit for relay 30 and the operating circuit for relay 31, both of these circuits having been traced in the foregoing de-

scription. When relay 16 releases after all of the pulses originated by the dialing of the third digit have been received relay 30 releases but relay 31 is locked to ground on lead 19. The release of relay 30 closes the circuit hereinbefore described for operating relay 33. Relay 33 locks, closes the circuit for operating relay 35, connects the pulsing circuit through brush 26 to the vertical magnet (not shown) of the final selector, connects busy potential battery through a low resistance through its outer left-hand armature and front contact to brush 24, and closes a circuit from battery through its outer left-hand armature and front contact, back contact and inner right-hand armature of relay 16, left-hand armature and front contact of relay 37, continuity contacts and winding of relay 32, next-to-the-outer left-hand armature and front contact of relay 33, and through brush 23 of switch M, to the sleeve brush of the final selector.

When the fourth and fifth digits of this five-digit number are dialed, the distributor circuit functions the same as when the third and fourth digits of the four-digit number were dialed, as hereinbefore described, except that the various circuits to and from the final selector pass through brushes 21, 22, 23, 24, 25 and 26 of switch M instead of through brushes 121, 122, 123, 124, 125 and 126 of switch S.

If the first digit of the called number is one which characterizes the number as being a five-digit number, level springs NP are actuated when the brushes of switch M are stepped up to the corresponding level. (If the five-digit numbers have different first digits which are not the same as any of the first digits of the four-digit numbers the NP springs are actuated on each of the corresponding levels). When relay 16 releases after all of the pulses originated by the dialing of the first digit have been received, relay 30 is operated and relay 36 is partially operated as hereinbefore described. The release of relay 16 also closes a circuit, for operating relay 37, which is traced from battery through the right-hand winding and normally closed continuity contacts of relay 37, through the contacts of NP springs 38, back contact and next-to-the-outer right-hand armature of relay 36, normally closed continuity contacts of relay 16, contacts of VON springs 18, to ground on lead 19. Relay 37 operates in this circuit and locks through the same winding and through its front contact and inner right-hand armature, to ground at relay 15. The operation of relay 37 prevents the further operation of switch S when the remaining digits of the called number are dialed. The release magnet 29 of switch M operates, when relay 16 releases, to restore the shaft and brushes of switch M to normal as hereinbefore de-

scribed. Relay 30 releases and relay 36 is completely operated and locked when the VON springs of switch M are restored to their normal positions.

When the second digit of this five-digit number is dialed relays 14, 15 and 16 function in the same manner as when the first digit was dialed and the vertical magnets 27 and 227 of switches M and T are operated in parallel to step their respective sets of brushes. The circuit for magnet 27 is the same as hereinbefore traced and the circuit for magnet 227 is from battery through its winding, right-hand winding of relay 230, and through the next-to-the-outer right-hand armature and front contact of relay 37, to ground as traced for magnet 27. Relay 230 is a two-stage relay and is partially operated in this circuit to close a circuit through its left-hand winding and locking contacts. When the shaft of switch M is stepped out of its normal position by the dialing of this second digit the circuit through the left-hand winding of relay 230 is closed at the contacts of VON springs 18, thus causing the complete operation of relay 230. The complete operation of relay 230 opens the circuit of stepping magnet 27 of switch M to prevent the further operation of switch M so that the remaining pulses originated by the dialing of the second digit are effective to step the brushes of switch T, only, to the corresponding level. When relay 16 releases after all of the pulses originated by the dialing of the second digit have been received relay 30 operates to transfer the pulsing circuit from vertical stepping magnet 227 to rotary stepping magnet 228 of switch T.

When the third digit of the called number is dialed relays 14, 15 and 16 and rotary magnet 228 function to advance the brushes 221, 222, 223, 224, 225 and 226 of switch T into contact with the corresponding set of terminals which connect to a final selector having access to the line of the called number. Relay 31 is operated and relay 30 holds when relay 16 is operated. When relay 16 releases after all of the pulses originated by the dialing of the third digit have been received, relay 30 is released but relay 31 holds to the ground on lead 19. The release of relay 30 closes the operating circuit for relay 33 as hereinbefore described. Relay 33 locks, causes the operation of relay 35, connects the pulsing circuit through brush 226 to the vertical magnet (not shown) of the final selector, connects busy potential (battery through a low resistance) to brush 224, and connects the winding of test relay 32 through brush 223 to the sleeve brush of the final selector.

When the fourth and fifth digits of the called number are dialed the circuit functions the same as hereinbefore described for a call to a line having a four-digit number,

when the third and fourth digits of a four-digit number were dialed, except that the various circuits to and from the final selector pass through brushes 221, 222, 223, 224, 225 and 226 of switch T instead of through brushes 121, 122, 123, 124, 125 and 126 of switch S.

When the trunk 9 is released on a call completed through the bank of switch T, switches M and S are returned to normal as hereinbefore described. The release magnet 229 of switch T is then operated in an obvious circuit to return the shaft and brushes of switch T to normal. Upon reaching their normal position the circuit of magnet 229 is opened at the contacts of VON springs 220 and ground is again connected to the winding of relay 14 in readiness for the next call.

For giving the trunk-offering operator at A access to the lines in an office of the above mentioned class (b) the switch T and its associated magnets and relay 230 are not required, and Fig. 3 and the NPA springs are not required. With this apparatus and wiring omitted the leads shown as connecting to the normally closed contacts of VON springs 220 are connected together, the leads shown as connecting to the back contact and inner left-hand armature of relay 230 are connected together, and the leads shown as connecting to the back contact and outer left-hand armature of relay 230 are connected together. All other leads shown as connecting to apparatus which is not furnished are omitted. In such an office the lines having four-digit numbers, i. e. from 2000 to 4899 inclusive, are accessible through sets of terminals in the bank of switch S and the lines having five-digit numbers, i. e. from 49,000 to 58,999 inclusive, are accessible through sets of terminals in the bank of switch M. The operation of the distributor switches M and S for calls to stations having four-digit numbers and for calls to stations having five-digit numbers whose first digit is the same as the first digit of some of the four-digit numbers is the same as that hereinbefore described for calls to similar numbers in an office of the above mentioned class (a). The operation of these switches on calls to stations having five-digit numbers whose first digit is different from the first digits of the four-digit numbers is somewhat different from that hereinbefore described for a call to such a station in an office within the above mentioned class (a). The brushes of switch M are stepped to the level corresponding to the first digit dialed and are restored to normal, relay 36 is partially and then completely operated, and relay 37 is operated all as hereinbefore described. When the second digit of the called number is dialed vertical magnet 27 of switch M steps the brushes of switch M to the corresponding level. The release of relay 16 after all of the pulses originated

by the dialing of the second digit have been received closes the circuit for operating relay 30. When the third digit is dialed rotary magnet 28 of switch M steps the brushes into contact with the corresponding set of terminals in the previously selected level. This set of terminals connects to a final selector which has access to the line of the called number. Relay 30 holds and relay 31 operates when relay 16 operates and relay 31 holds and relay 30 releases when relay 16 releases after all of the pulses originated by the dialing of the third digit have been received. The release of relay 30 closes the circuit for operating relay 33. Relay 33 locks, operates relay 35, connects the pulsing circuit through brush 26 to the vertical magnet (not shown) of the final selector, connects busy potential to brush 24, and connects the winding of test relay 32 through brush 23 to the sleeve brush of the final selector. When the fourth and fifth digits of the called number are dialed the call is completed in the same manner as hereinbefore described for a call to a line having a four-digit number in an office of class (a) except that the various circuits to and from the final selector pass through the brushes of switch M instead of through the brushes of switch S.

For giving the trunk-offering operator access to the lines in an office of the above mentioned class (c) the distributor switches are arranged the same as for an office of class (b) except that level springs NP are not furnished. The lines having the four-digit numbers, i. e. from 2000 to 4899 inclusive, are accessible through the bank of switch S and the lines having the five-digit numbers, i. e. from 49,000 to 49,999 inclusive, are accessible through the bank of switch M. Calls to lines in such an office are completed in the same manner as hereinbefore described for calls to similarly numbered lines in an office of the above mentioned class (a).

For giving the trunk-offering operator access to the lines in an office of the above mentioned class (d) switches S and T and their associated magnets, relay 230, and level springs NP are not furnished but relay 43 and wiring as shown in Fig. 3 is furnished and level springs NPA are furnished and set to be actuated on those levels which correspond to the second digit of five-digit numbers. The leads shown as connecting to the normally closed contacts of VON springs 120 are connected together; the leads shown as connecting to the back contact and inner left-hand armature of relay 230 are connected together, the leads shown as connecting to the back contact and outer left-hand armature of relay 230 are connected together, and Fig. 3 is inserted in Fig. 2 at the sections designated AA and A'A'. The lines having four-digit numbers, i. e. 6100 to 6699 inclusive, are accessible through the first set of termi-

nals on each of the levels corresponding to the second digit, i. e. levels 1 to 6 inclusive; and the lines having five-digit numbers, i. e. 67,000 to 69,999 inclusive are accessible through the sets of terminals on the levels which correspond to the second digit, i. e. levels 7 to 9 inclusive.

The dialing of the first digit steps the brushes up to the corresponding level from which they are returned to normal as hereinbefore described. The operation of level springs NPA when the first digit is dialed is ineffective. Relay 36 operated partially when the shaft moved off-normal and operated completely when the shaft and brushes were restored to normal. The complete operation of relay 36 renders the NPA springs effective if the second digit is such as to step the brushes up to the level or levels on which these springs are actuated. In this event the release of relay 16, after all of the pulses originated by the dialing of the second digit have been received and the brushes have been stepped up to the corresponding level, closes a circuit for operating relay 37. This circuit may be traced from battery through the right-hand winding and continuity contacts of relay 37, contacts of NPA springs 39, front contact and next-to-the-outer right-hand armature of relay 36, normally closed contacts of the continuity springs of relay 16, contacts of VON springs 18, to ground on lead 19. Relay 37 locks, connects the winding of test relay 32 to brush 24. Relay 36 is first partially operated and then completely operated and relay 30 is operated and released as hereinbefore described. When the second digit of the called number is dialed the brushes of switch M are stepped to the corresponding level. Relay 30 operates when relay 16 releases after all of the pulses originated by the dialing of the second digit have been received. When the third digit is dialed the rotary magnet 28 is operated to step the brushes of switch M into contact with the corresponding set of terminals which connect to a final selector having access to the line of the called number. When relay 16 releases after all of the pulses originated by the dialing of the third digit have been received relay 33 operates and the call is completed as controlled by the dialing of the fourth and fifth digits of the number in the same manner as hereinbefore described for a call to a line having a five-digit number whose first digit is the same as the first digit of some of the four-digit numbers in an office of the above mentioned class (a).

If the called number is a four-digit number the dialing of the second digit steps the brushes up to a level on which the NPA springs are not actuated and relay 37 is not operated. The operation of relay 30, when relay 16 releases after all of the pulses originated by the dialing of the second digit have been received, closes a circuit for operating relay 43. This circuit may be traced from battery through the winding of relay 43, back contact and outer right-hand armature of relay 37, front contact and inner right-hand armature of relay 36, back contact and outer right-hand armature of relay 16, front contact and outer right-hand armature of relay 30, contact of VON spring 18, to ground on lead 19. The operation of relay 43 closes on obvious circuit for operating relay 31 and closes an obvious circuit for operating the rotary stepping magnet 28 of switch M. The brushes of switch M are therefore advanced before the dialing of the third digit into con-

tact with the first set of terminals in the level which corresponds to the second digit of the called number. This set of terminals connects to a final selector which has access to the line of the called number and the call is completed in the same manner as has hereinbefore been described for a call completed through the brushes of switch M to a line in an office of the above mentioned class (a).

For giving the trunk-offering operator at A access to the lines in an office of the above mentioned class (e) the distributor circuit includes apparatus and wiring the same as for an office of class (d) except that the NPA springs and relay 43 of Fig. 3 are not furnished and the leads shown as connecting to the contacts of NP springs 38 are connected together. The lines of all numbers are accessible through the bank of switch M. The shaft and brushes of switch M are advanced in a vertical direction by the dialing of the first digit and are then restored to normal as hereinbefore described. When relay 16 releases after all of the pulses originated by the dialing of the first digit have been received relay 37 is operated (on every call) by the circuit through its right-hand winding. Relay 37 locks and connects the winding of test relay 32 to brush 24. Relay 36 is first partially operated and then completely operated and relay 30 is operated and released as hereinbefore described. When the second digit of the called number is dialed the brushes of switch M are stepped to the corresponding level. Relay 30 operates when relay 16 releases after all of the pulses originated by the dialing of the second digit have been received. When the third digit is dialed the rotary magnet 28 is operated to step the brushes of switch M into contact with the corresponding set of terminals which connect to a final selector having access to the line of the called number. When relay 16 releases after all of the pulses originated by the dialing of the third digit have been received relay 33 operates and the call is completed as controlled by the dialing of the fourth and fifth digits of the number in the same manner as hereinbefore described for a call to a line having a five-digit number whose first digit is the same as the first digit of some of the four-digit numbers in an office of the above mentioned class (a).

For giving the trunk-offering operator at A access to the lines in an office of the above mentioned class (f) switch S and its associated magnets and relay 43 of Fig. 3 are not furnished but both of the level springs NP and NPA are furnished. The lines having numbers beginning with a certain first digit, i. e., from 50,000 to 59,999 inclusive, are accessible through sets of terminals in the bank of switch M and the NPA springs are actuated on the corresponding level. The lines having numbers beginning with other first

5 digits, i. e., from 60,000 to 62,999 inclusive or from 48,999 to 49,999 inclusive and from 10 60,000 to 62,999 inclusive, are accessible through sets of terminals in the bank of switch T and the NP springs are actuated on the corresponding level or levels. If the level 15 to which the brushes are stepped by the dialing of the first digit is one on which the NP springs are actuated relay 37 operates when relay 16 releases after all of the pulses originated by the dialing of the first digit have been received. The call is completed through the brushes of switch T in the same manner 20 as hereinbefore described for a call to a line having a five-digit number whose first digit is different from the first digits of the four-digit numbers in an office of the above mentioned class (a).

If the level to which the brushes are stepped 25 by the dialing of the first digit is that on which the NPA springs are actuated relay 37 is not operated until relay 16 releases after all of the pulses originated by the dialing of the second digit have been received. The brushes of switch M are returned to normal 30 and relay 36 is partially and then completely operated in the same manner as hereinbefore described. The dialing of the second digit is effective to operate the vertical stepping magnet of switch M, and when relay 16 releases after all of the pulses have been received relay 37 operates in the circuit from battery through its right-hand winding and continuity contacts, contacts of NPA 35 springs 39, front contact and next-to-the-outer right-hand armature of relay 36, normally closed contacts of the continuity springs of relay 16, contacts of VON springs 18, to ground on lead 19. The call is completed through the brushes of switch M in the same manner as hereinbefore described 40 for a call to a line having a five-digit number whose first digit is the same as the first digit of some of the four-digit numbers in an office of the above mentioned class (a).

45 While the drawings disclose the embodiment of the invention in a trunk-offering distributor circuit, the invention is not limited to such an arrangement and may be applied wherever selective operation of one or more switches is desired in response to a number 50 of control conditions which may or may not exceed the total number of different selective operations which the switch or switches are capable of effecting without the repetition 55 of one or more of the operations.

What is claimed is:

1. In a telephone system, lines having 60 numbers which are composed of a given number of digits, lines having numbers which are composed of a different number of digits, an automatic switch, final selectors directly accessible to said switch, and means in said switch responsive to pulses originated by the 65 dialing of two or more successive digits

of the number of a line to select a final selector having access to said line.

2. In a telephone system, a first group of lines having numbers which are composed of a given number of digits, a second group of lines having numbers which are composed of a different number of digits but which have the same first digit as the numbers of some of the lines in said first group, a third group of lines having numbers which are composed of said different number of digits but which do not have the same first digit as the numbers of any of the lines in said first group, an automatic switch, final selectors directly accessible to said switch, and means in said switch responsive to pulses originated by the dialing of two or more successive digits of the number of a line to select a final selector having access to said line. 70 75 80

3. In a telephone system, a first group of lines having numbers which are composed of a given number of digits, a second group of lines having numbers which are composed of a different number of digits but which have the same first digit as the number of some 90 of the lines in said first group, an automatic switch, final selectors directly accessible to said switch, and means in said switch responsive to pulses originated by the dialing of two or more successive digits of the number of a line to select a final selector having access to said line. 95

4. In a telephone system, a first group of lines having numbers which are composed of a given number of digits and which all have the same first digit, a second group of lines having numbers which are composed of a different number of digits but which have the same first digit as the numbers of the lines in said first group, an automatic 100 switch, final selectors directly accessible to said switch, and means in said switch responsive to pulses originated by the dialing of two or more successive digits of the number of a line to select a final selector having 105 access to said line. 110

5. In a telephone system, a first group of lines having numbers which are composed of a given number of digits, a second group of lines having numbers which are composed of said given number of digits but which do not have the same first digit as the numbers of any of the lines in said first group, an automatic switch, final selectors directly accessible to said switch, a called line, means responsive to the dialing of successive digits of the number of said called line to select a final selector having access to said called line, and means in said automatic switch responsive to the dialing of the succeeding digits of the number of said called line for controlling said final selector to establish connection with said called line. 115 120

6. In a telephone system, lines having 125 numbers composed of a given number of

digits, an automatic switch, final selectors directly accessible to said switch, a called line, means responsive to the dialing of successive digits of the number of said called line to select a final selector having access to said called line, and means in said switch responsive to the pulses originated by the dialing of the succeeding digits of the number of said called line for controlling said final selector to establish connection with the said called line.

7. In a telephone system, lines having numbers composed of a given number of digits, lines having numbers composed of a different number of digits, an automatic switch, final selectors directly accessible to said switch, means for discriminating between numbers composed of said given number of digits and numbers composed of said different number of digits, and means responsive to pulses originated by the dialing of two or more successive digits of the number of a line to select a final selector having access to said line.

25 8. In a telephone system, a first group of lines having numbers which are composed of a given number of digits, a second group of lines having numbers which are composed of a different number of digits but which 30 have the same first digit as some of the numbers of lines in said first group, a third group of lines having numbers which are composed of said different number of digits but which do not have the same first digit as any of 35 the numbers of lines in said first group, a main distributor switch including a set of brushes and a terminal bank, means for advancing the brushes of said main switch, final selectors directly accessible to said main 40 switch, a secondary distributor switch including a set of brushes and a terminal bank, means for advancing the brushes of said secondary switch, final selectors directly accessible to said secondary switch, a tertiary 45 distributor switch including a set of brushes and a terminal bank, means for advancing the brushes of said tertiary switch, final selectors directly accessible to said tertiary switch, means common to all of said switches 50 for receiving pulses originated by the dialing of successive digits of the number of any 55 of said lines, and means for distinguishing between the numbers of the lines in each of said groups from the numbers of the lines in the other two of said groups.

5. In a telephone system, lines, some of said lines having numbers composed of a given number of digits, others of said lines having numbers composed of a different number of digits, a main distributor switch including a set of brushes and a terminal bank, means for advancing the brushes of said main switch, an auxiliary distributor switch including a set of brushes and a terminal bank, 65 means for advancing the brushes of said aux-

iliary switch, means common to both of said switches for receiving pulses originated by the dialing of successive digits of the number of any of said lines and for simultaneously controlling both of said switches, and means for distinguishing between numbers composed of said given number of digits and numbers composed of said different number of digits.

10. In a telephone system, a first group of lines having numbers which are composed of a given number of digits, a second group of lines having numbers which are composed of said given number of digits but whose first digit differs from the first digit of the numbers of all of the lines in said first group, a main distributor switch including a set of brushes and a terminal bank, means for advancing the brushes of said main switch, final selectors directly accessible to said main switch, an auxiliary distributor switch including a set of brushes and a terminal bank, means for advancing the brushes of said auxiliary switch, final selectors directly accessible to said auxiliary switch, means common to both of said switches for receiving pulses originated by the dialing of successive digits of the number of a line in either of said groups, means for distinguishing between the number of a line in said first group and the number of a line in said second group, and means responsive to pulses originated by the dialing of successive digits of the number of a line to select a final selector having access to said line.

11. In a telephone system, lines having numbers which are composed of a given number of digits, lines having numbers which are composed of a different number of digits, an automatic switch, final selector directly accessible to said switch, means for distinguishing between numbers composed of said given number of digits and numbers composed of said different number of digits, a called line, means in said switch responsive to pulses originated by the dialing of successive digits of the number of said called line to select a final selector having access to said called line, and means in said automatic switch responsive to the dialing of the succeeding digits of the number of said called line for controlling said final selector to establish connection with said called line.

12. In a telephone system, a first group of lines having numbers which are composed of a given number of digits, a second group of lines which are composed of a different number of digits, a main distributor switch including a set of brushes and a terminal bank, means for advancing the brushes of said main switch, final selectors connected to the sets of terminals in the bank of said main switch, a secondary distributor switch including a set of brushes and a terminal bank, means for advancing the brushes of said sec-

- ondary switch, final selectors connected to the sets of terminals in the bank of said secondary switch, means for distinguishing between the numbers of lines in said first group from the numbers of lines in said second group, a called line, means responsive to pulses originated by the dialing of successive digits of the number of said called line to select a final selector having access to said called line, and means in and common to said distributor switches responsive to the pulses originated by the dialing of the succeeding digits of the number of said called line for controlling said final selector to establish connection with said called line. 5
13. In a telephone system, a first group of lines having numbers which are composed of a given number of digits, a second group of lines which are composed of a different number of digits, a main distributor switch including a set of brushes and a terminal bank, means for advancing the brushes of said main switch, final selectors connected to the sets of terminals in the bank of said main switch, a secondary distributor switch including a set of brushes and a terminal bank, means for advancing the brushes of said secondary switch, final selectors connected to the sets of terminals in the bank of said secondary switch for distinguishing a call to a line in said second group, a called line, means responsive to pulses originated by the dialing of two or more successive digits of the number of a line to select a final selector having access to said line, and means in and common to said distributor switches responsive to the pulses originated by the dialing of the succeeding digits of the number of said called line for controlling said final selector to establish connection with said called line. 10
14. In a telephone system, a first group of lines having numbers which are composed of a given number of digits, a second group of lines having numbers which are composed of a different number of digits, a two-motion distributor switch including a set of brushes and a terminal bank, final selectors connected to the sets of terminals in said bank, a called line, means responsive to the dialing of a digit of the number of said called line for advancing said brushes in a vertical movement, means for returning said brushes to normal after said vertical movement, means responsive to the dialing of the first succeeding digit of the number of said called line for advancing the brushes in a rotary movement into contact with a set of terminals which are connected to a final selector having access to said called line, and means in said automatic switch responsive to the pulses originated by the dialing of the remaining digits of the number of said called line for controlling said final selector to establish connection with said called line. 15
15. In a telephone system, lines composed of a given number of digits, a two-motion automatic switch including a set of brushes and a terminal bank, means for advancing said brushes in a vertical movement, means for advancing said brushes in a rotary movement, final selectors connected to the sets of terminals in said bank, a called line, means responsive to the dialing of a digit of the number of said called line for advancing said brushes in a vertical movement, means for returning said brushes to normal after said vertical movement, means responsive to the dialing of the first succeeding digit of the number of said called line for advancing said brushes in a second vertical movement, means responsive to the dialing of the second succeeding digit of the number of said called line for advancing the brushes in a rotary movement into contact with a set of terminals which are connected to a final selector having access to said called line, and means in said automatic switch responsive to the pulses originated by the dialing of the remaining digits of the number of said called line for controlling said final selector to establish connection with said called line. 20
16. In a telephone system, a first group of lines having numbers which are composed of a given number of digits, a second group of lines having numbers which are composed of said given number of digits but whose first digit differs from the first digit of the number of any of the lines in said first group, a two-motion main distributor switch including a set of brushes and a terminal bank, final selectors directly accessible to said main switch, a two-motion auxiliary distributor switch including a set of brushes and a terminal bank, final selectors directly accessible to said auxiliary switch, means common to both switches for receiving pulses originated by the dialing of successive digits of the number of a line in either of said groups, a called line, means responsive to the dialing of a digit of the number of said called line for advancing said brushes in a vertical movement, means for returning said brushes to normal after said vertical movement, means responsive to the dialing of the first succeeding digit of the number of said called line for advancing the brushes in a second vertical movement, means including contacts actuated on certain levels of said switch for distinguishing calls to lines in said second group, means effective without further dialing to advance said brushes in a rotary movement into contact with a set of terminals which are connected to a final selector having access to said called line if said called line is in said first group, means responsive to 25
- 30
- 35
- 40
- 45
- 50
- 55
- 60
- 65

ber of said called line for advancing the brushes of said main switch in a vertical movement, means including contacts actuated on certain levels of said main switch for distinguishing the number of a line in said second group, means for returning the brushes of said switch to normal after said vertical movement, means responsive to the dialing of the first succeeding digit of the number of said called line if said called line is in said second group for advancing the brushes of said main switch one step in a second vertical movement and for advancing the brushes of said auxiliary switch in a first vertical movement to the level corresponding to the said first succeeding digit, means responsive to the dialing of the second succeeding digit of the number of said called line for advancing the brushes of said auxiliary switch in a rotary movement into contact with a set of terminals which are connected to a final selector having access to said called line.

10 5 15 20 25 30 35 40 45 50 55 60 65 70 75 80 85 90 95 100 105 110 115 120 125 130

17. In a telephone system, a first group of lines having numbers composed of a given number of digits, a second group of lines having numbers composed of a different number of digits, a two-motion main distributor switch including a set of brushes and a terminal bank, final selectors directly accessible to said main switch, a two-motion secondary distributor switch including a set of brushes and a terminal bank, final selectors directly accessible to said secondary switch, means common to both of said switches for receiving pulses originated by the dialing of successive digits of the number of a line in either of said groups, a called line, means responsive to the dialing of a digit of the number of said called line for advancing the brushes of both of said switches in a vertical movement, means for returning the brushes of said main switch after said vertical movement, means responsive to the dialing of the first succeeding digit of the number of said called line for advancing the brushes of said main switch in a second vertical movement and for advancing the brushes of said secondary switch into contact with a set of terminals corresponding to said first succeeding digit, a final selector connected to said terminals for giving access to said called line if said called line is in said

first group, means including one terminal of said set of terminals for distinguishing the number of said called line if said called line is in said second group, and means responsive to the dialing of the second succeeding digit of the number of said called line if said called line is in said second group for advancing the brushes of said main switch in a rotary movement into contact with a set of terminals which are connected to a final selector having access to said called line.

18. In a telephone system, a first group of lines having numbers composed of a given number of digits, a second group of lines having numbers composed of a different number of digits, a two-motion main distributor switch including a set of brushes and a terminal bank, final selectors directly accessible to said main switch, a two-motion secondary distributor switch including a set of brushes and a terminal bank, final selectors directly accessible to said secondary switch, means common to both of said switches for receiving pulses originated by the dialing of successive digits of the number of a line in either of said groups, a called line, means responsive to the dialing of a digit of the number of said called line for advancing the brushes of both of said switches in a vertical movement, means including contacts actuated on certain levels for distinguishing the number of said called line if said called line is in said second group, means for returning the brushes of said main switch to normal after said vertical movement, means responsive to the dialing of the first succeeding digit for advancing the brushes of said main switch in a second vertical movement to the corresponding level, means responsive to the dialing of said first succeeding digit for advancing the brushes of said secondary switch in a rotary movement into contact with the corresponding set of terminals if said called line is in said first group, and means responsive to the dialing of the second succeeding digit for advancing the brushes of said main switch into contact with the corresponding set of terminals if said called line is in said second group.

In witness whereof, I hereunto subscribe my name this sixth day of February, 1929.

JOHN R. GOULD.
